UNITED STATES PATENT OFFICE.

RODNEY G. RICHARDSON, OF CHICAGO, ILLINOIS, ASSIGNOR TO AUTOMATIC ELECTRIC COMPANY, OF CHICAGO, ILLINOIS, A CORPORATION OF ILLINOIS.

TRUNKING ARRANGEMENT FOR AUTOMATIC TELEPHONE SYSTEMS.

Application filed October 11, 1921. Serial No. 507,009.

To all whom it may concern:

Be it known that I, RODNEY G. RICHARDSON, a citizen of the United States of America, and a resident of Chicago, Cook County, and State of Illinois, have invented certain new and useful Improvements in Trunking Arrangement for Automatic Telephone Systems, of which the following is a specification.

10 The present invention relates to trunking arrangements for automatic telephone systems in general, but is concerned more particularly with trunking arrangements for such systems as employ non-numerical trunk selecting switches that are seized by automatic selector switches; and the principal object, briefly stated, is the provision of new and improved trunking arrangements whereby the trunk selecting 15 movement of a non-numerical switch in a system of this type, or the maximum number of trunks which such a switch will have to test to find an idle one, is considerably reduced.

20 Another object is to provide an improved non-numerical switch using a plurality of relays to select an idle trunk instead of the usual step by step movement.

25 Still another object is to provide improved circuits for rendering all the trunks incoming to a particular secondary group busy while the trunks outgoing from that group are all in use.

30 A still further object is the provision of new and improved circuit arrangements whereby the operation of a selector switch is improved.

35 These objects, together with others that are not specifically pointed out now, will be 40 more fully pointed out hereinafter, reference being had to the accompanying drawings comprising Figs. 1-5, inclusive, which show by means of the usual circuit diagrams sufficient of the apparatus employed in a 45 system embodying the principles of the invention to enable the same to be understood.

45 In the drawings, Figs. 1 and 2, when placed together with Fig. 1 over Fig. 2 and with the corresponding lines at the ends of 50 the sheets in alignment, represent a trunking layout in which a major group of thirty trunks shown on the right hand side of the two sheets is accessible through non-numerical switches to the major group of fifty

trunks shown on the left hand side of the 55 two sheets.

Figs. 3 and 4, when arranged in order with the corresponding lines in alignment, represent sufficient of the apparatus used in the trunking layout shown in Figs. 1 60 and 2 to enable the same to be understood.

Fig. 5 is a circuit diagram showing a group of non-numerical switches which are different from those shown in Fig. 3. These switches are of a type which may also be 65 used in a layout such as is shown in Figs. 1 and 2, and for convenience it will be assumed that the system includes both types of switches.

Referring now particularly to Figs. 1 and 70 2, the trunking layout shown therein will be explained more in detail. It has heretofore been the practice, when the so called plunger type of non-numerical switches are used in similar layouts, to divide the major 75 group of outgoing trunks, or the group which corresponds to the group shown on the right hand side of the two drawings, into subgroups of ten trunks each, in accordance with the number of trunks to which 80 a plunger type switch has access. Similarly, when step by step rotary non-numerical switches are used the practice has been to divide the major group of outgoing trunks into subgroups of twenty five trunks each, 85 in accordance with the number of trunks to which a switch of this type has access. This practice, so far as is known, has been followed invariably, regardless of the number 90 of trunks in the major group. In the present case, however, the major group of outgoing trunks is preferably divided into ten subgroups, corresponding to the number of trunks to which a selector switch has access 95 in any one level. As shown, there are thirty outgoing trunks in the major group and consequently there are three outgoing trunks in each subgroup. If the major group comprised forty outgoing trunks then each subgroup would comprise four trunks, or if the 100 major group comprised only twenty trunks then each subgroup would comprise only two trunks. It will be seen now that as long as the major group of outgoing trunks is less than 100 there will not be as many as ten trunks per subgroup, which heretofore 105 has been the minimum number, and with major groups of a number much less than

100 the number of trunks in each subgroup is correspondingly less and consequently the switches which have access to these subgroups of trunks have a correspondingly 5 smaller maximum number of trunks to test in order to find an idle one.

It will be seen from an examination of the drawings that there is a trunk line extending from each selector group on the 10 left to a non-numerical switch in each subgroup on the right. In the first group of selector trunks, the group in the upper left hand corner of Fig. 1, the first trunk leads to a non-numerical switch in the first subgroup, or the subgroup in the upper right hand corner of Fig. 1. The second trunk in this selector group leads to a switch in the second subgroup, the third trunk to a switch in the third subgroup and so on. 15 The trunks from the second group of selectors extend to switches in the several subgroups in the same manner as those from the first selector group, except that a slip is introduced and trunk No. 1 in the second selector group leads to a switch in the third subgroup, the second trunk to a switch in the fourth subgroup, and so on down to the last trunk in this group which leads to a switch in the second subgroup. It will 20 be observed that this same slip is carried out all along down the line. This slip distributes the traffic evenly amongst the various subgroups.

This revision of the trunking arrangement, in decreasing the number of trunks in each subgroup, not only decreases the time required for an idle trunk to be selected, but when relay switches are used effects a great saving in equipment for the 25 reason that the number of relays in such a switch is proportionate to the number of trunks to which the switch has access.

Referring now particularly to Fig. 3, the selector D shown therein is mechanically of the usual vertical and rotary type and accordingly has its bank contacts arranged in horizontal rows or levels. This switch is operated according to the well known two-wire system of control. The circuits of this switch are shown complete and will be described fully hereinafter.

The non-numerical switch E³, which is accessible to the selector D, does not have the usual mechanical trunk selecting movement but has instead a plurality of relays which operate one after the other to select an idle trunk. The circuits of this switch also are shown complete and will be described fully hereinafter.

Each of the trunks to which the switch E³, together with the other switches in the same group, has access, is assumed to extend to a repeater, such as the repeaters F, F', and F², Figure 4, and thence by way of a two conductor trunk line such as the trunk

lines X, X', and X² to another office in the system. These repeaters F, F', and F² are all identical with each other and, with the exception of an added relay, are identical with the two-wire repeaters that are now in common use.

The relay group RG shown in the lower part of Fig. 4 is used for the purpose of making all the trunks incoming to the group busy as soon as all the outgoing 75 trunks are taken for use, or rather, as soon as the last call arrives at the group. This operation will be explained more fully hereinafter.

Of the switches H, H', H², H³, and H⁴, 80 Fig. 2, and of which only H, H' and H⁴ are shown in the detailed circuit drawing in Fig. 5, each is similar to the switch E³, Fig. 3, in that no mechanical step by step arrangement is employed to pick out an 85 idle trunk line, but are different in that the trunks are preselected as will be explained more fully hereinafter.

The apparatus having been described more or less in general will now be described in connection with a detailed description of its operation. For this purpose, it will be assumed that a call comes through the exchange by way of the selector D, Fig. 3. The selector D, it may be pointed out, is one of the selectors which has access to the second group of trunk lines on the left of Fig. 2, counting from the bottom. We shall assume further that when the call comes in none of the switches E—E⁴, inclusive, Fig. 2, are in use and consequently all of the trunks outgoing from that subgroup are idle at this time. When the call 90 comes in as assumed, the selector D is seized at the bank contacts 2, 3, and 4, or their multiples, in which the trunk line comprising conductors 5, 6, and 7 terminates, and line relay 10 is energized over the calling subscriber's loop in series with the impulse springs of the calling subscriber's calling device. Upon energizing, line relay 10 closes a circuit for release relay 11, including the resting contact of armature 30 of switching relay 14 and said armature, at armature 15. Release relay 11, upon energizing, opens a 95 point in the circuit of release magnet 19 and closes a point in the circuit of slow acting relay 12 at armature 17, and at armature 16 places ground on release trunk conductor 6, thereby establishing a holding circuit 100 for the switching relay of the switch which seized the selector D.

The calling subscriber now manipulates his calling device in accordance with the next digit in the desired number, thereby producing a corresponding number of interruptions in the circuit of line relay 10. As soon as line relay 10 falls back in response to the first interruption produced in its circuit, it closes at armature 15, the cir- 105 110 115 120 125 130

cuit of the slow acting relay 12. The slow acting relay 12, upon energizing, prepares the circuit of stepping relay 13 at armature 22 and at armature 21 opens a point in the 5 circuit of rotary magnet 23 and closes a point in the circuit of vertical magnet 20. Each time line relay 10 energizes at the end of an interruption produced in its circuit it opens the circuit of slow acting relay 12 and closes the circuit of release relay 11 and vertical magnet 20 in multiple. Relays 11 and 12, being slow acting, are both maintained energized throughout the series of 10 interruptions. By the operation of the vertical magnet, which energizes each time its circuit is closed following an interruption in the circuit of the line relay 10, the switch shaft and wipers are raised step by step until the latter come to rest opposite the 15 desired level of contacts, which will be assumed to be the level in which the trunk line comprising conductors 38—40, inclusive, terminates. As soon as the shaft of the switch is moved from its normal position the 20 off-normal springs 26 close, thereby completing a circuit for stepping relay 13. Stepping relay 13, upon energizing, closes a locking circuit for itself at armature 25 in series with interrupter contacts 27, and 25 at armature 24 prepares a circuit for rotary magnet 23. After the last interruption is produced in the circuit of line relay 10, armature 15 comes to rest against its working contact thus leaving the circuit of slow 30 acting relay 12 open. Upon deenergizing, relay 12 opens the initial circuit of stepping relay 13 at armature 22 and at armature 21 opens the circuit of vertical magnet 20 and closes the circuit of rotary magnet 23. Rotary magnet 23, upon energizing, advances the wipers 32—34, inclusive into engagement with the first set of contacts in the level opposite which they are raised. Near the end of its stroke rotary magnet 23 separates the 35 interrupter contacts 27, thereby opening the circuit of stepping relay 13. Stepping relay 13, upon deenergizing, opens another point in its circuit at armature 25 and at armature 24 opens the circuit of rotary magnet 23. Rotary magnet 23 now deenergizes and closes the interrupter contacts 27 again. 40 From this point, the operation depends upon whether the trunk line which terminates in the first set of contacts is busy or idle. If it is busy, test wiper 33 is in engagement with a grounded contact and stepping relay 13 energizes again over a circuit which includes wiper 33 and armature 29 and its resting contact. Upon energizing, stepping 45 relay 13 closes the previously described locking circuit for itself at armature 25 and at armature 24 closes the circuit of rotary magnet 23. Rotary magnet 23, upon energizing, steps the wipers into engagement with the 50 next set of contacts and again opens its in- 55

terrupter contacts 27. This alternate operation of the rotary magnet and stepping relay continues until an idle trunk is found. In the present case, however, it has been assumed that the switches E—E⁴, inclusive, 70 Fig. 2, are idle and consequently the trunk line terminating in bank contacts 35—37, inclusive, which is the first set of contacts in the level, is idle, when the call is made as described. This being the case, there is no 75 direct circuit closed for stepping relay 13 when wiper 33 arrives upon test contacts 36 and the switching relay 14 which has heretofore been short circuited immediately energizes over the following path: From 80 ground by way of the working contact of armature 16 and the said armature, switching relay 14, interrupter contacts 27, off-normal contacts 26, and stepping relay 13 to battery. Stepping relay 13, however, being 85 wound with comparatively few turns is not able to energize over this circuit on account of the high resistance of switching relay 14. Switching relay 14, upon energizing, disconnects test wiper 33 from a point between its 90 own winding and that of stepping relay 13 and connects it to the release trunk conductor 6 at armature 29; removes ground from the armature of line relay 10 at armature 30; and at armatures 28 and 31 disconnects the trunk conductors 5 and 7 from the upper and lower windings of line relay 10 and extends them by way of the working 95 contacts of the said armatures, line wipers 32 and 34, bank contacts 35 and 37, trunk conductors 38 and 40, armatures 58 and 61 and their resting contacts to the winding of line relay 50 of switch E³ and ground, respectively. Line relay 50, upon energizing, 100 places ground upon release trunk conductor 39 at armature 57, thereby establishing a holding circuit for the selector D and the switches back of it before the slow acting release relay 11 has had time to deenergize. It will be noted that as soon as ground 105 is placed on release trunk conductor 39 by the pulling up of switching relay 14 of the switch D, the seized trunk is made busy immediately to the other switches having access to it. In this case, however, not only 110 the seized trunk but also all the other trunks incoming to this group of switches is made busy through the common conductor 90 to which all the release trunk conductors are normally connected through the resting contacts of armature 60, 60', 60² etc. It is seen now that any other call which comes in at this stage will not take a trunk leading to the group in which the switch E³ is located 115 but will be diverted to some other group. To continue with the operation of the switch E³, line relay 50, upon energizing, in addition to placing ground on release trunk conductor 39 as described, closes at armature 120 56 the following circuit: From ground by 125

130

way of armature 56 and its working contact, switching relay 51, armature 69 and its resting contact, armature 74 and its resting contact, and the lower winding of the relay 54 to battery. This circuit, it will be noted, includes relay 51 and the lower winding of the relay 54 in series. As a further result of the operation of line relay 50, armature 55 is connected to a point between the winding 10 of relay 51 and the lower winding of relay 54. Armature 55 is normally connected to ground through the resting contact of armature 59 and said armature, armature 63 and its resting contact, armature 67 and its resting contact, and armature 72 and its resting contact. Switching relay 51 is accordingly short circuited and prevented from energizing. Relay 54, however, energizes; closes a locking circuit for itself at armature 73; 20 disconnects ground from the point between its lower winding and that of switching relay 51 at armature 72 and connects up release trunk conductor 77 instead; disconnects its own lower winding and connects up the 25 lower winding of relay 53 at armature 74; and at armatures 71 and 75 connects up the upper and lower series of contacts and armatures to trunk conductors 76 and 78.

From this point the operation depends 30 upon whether the trunk line comprising conductors 76-78, inclusive, is busy or idle. If it is busy release trunk conductor 77 is grounded and switching relay 51 is still short circuited. With this condition existing relay 53 energizes; closes a locking circuit for its own upper winding and opens the locking circuit of switching relay 54 at armature 68; connects the point between its own lower winding and the winding of 35 switching relay 51 to release trunk conductor 80 at armature 67; disconnects its own lower winding and connects up the lower winding of relay 52 at armature 69; and at armatures 66 and 70 disconnects the trunk 40 conductors 76 and 78 and connects up the trunk conductors 79 and 81. Relay 54 de-energizes now in response to the opening of 45 its locking circuit but does not perform any particular function at this time. If the 50 trunk line comprising conductors 79-81, inclusive, is busy at this time there is a ground potential on release trunk conductor 80 and relay 52 by action identical with that of relay 53, just described, transfers the connection to the trunk line comprising conductors 82-84, inclusive, and relay 53 deenergizes.

In the present case, however, we shall assume, as before stated, that the trunk line 55 comprising conductors 76-78, inclusive, is idle at this time and consequently there is no ground potential on release trunk conductor 77, and as soon as relay 54 has energized and transferred the circuits in the manner described, switching relay 51 ener-

gizes in series with the lower winding of relay 53. Relay 53, however, does not energize in series with the switching relay 51 on account of the high resistance of the said switching relay 51. Switching relay 51, upon energizing, disconnects release trunk conductor 77 from the point between its own winding and the lower winding of relay 53 at armature 59 and connects it to ground through the working contact of armature 56 and said armature, thus causing the seized trunk to test busy immediately to the other switches having access to it; disconnects release trunk conductor 39 from the common conductor 90 at armature 60 and connects it by way of the previously traced series of armatures and contacts to release trunk conductor 77; and at armatures 58 and 61 disconnects trunk conductors 38 and 40 from the winding of relay 50 and ground, respectively, and extends them by way of armatures 62 and 65 and their resting contacts, armatures 66 and 70 and their resting contacts, armatures 71 and 75 and their working contacts, trunk conductors 76 and 78, and the normally closed contacts controlled by armatures 110 and 111 to the upper and lower windings of the double wound line relay 102 of repeater F. Line relay 102 now energizes over the calling subscriber's loop and at armature 113 opens a point in the circuit of slow acting relay 103 and closes a circuit for relays 104 and 105 in multiple. Relay 105, upon energizing, among other things which will be pointed out more fully hereinafter, disconnects relay 104 from the working contact of armature 113 and substitutes a circuit through armature 120 and its working contact. Relay 104, upon energizing, places ground upon release trunk conductor 77 at armature 117. This occurs before the slow acting line relay of the switch E^s has had time to deenergize and maintains a holding circuit for the switch E^s and other switches behind it.

Returning now to the repeater F, as a further result of the energization of relay 104, it closes at armature 119 a circuit for the lower winding of electropolarized relay 106. This winding alone, however, consisting of a small number of turns of a relatively high resistance, is not able to effectively energize the relay. As a still further result of the energization of relay 104 it prepares a circuit for slow acting relay 103 at armature 118, and at armature 116 completes a bridge across the conductors of the trunk line X as follows: From the lower conductor of trunk line X by way of the working contact of armature 114 and said armature, right hand winding of impedance 107, normally closed contacts controlled by armature 112, upper winding of electropolarized relay 106, rest- 125 130

- ing contact of armature 115 and said armature, and the working contact of armature 116 and said armature to the upper conductor of trunk line X. In response to the closure of this bridge, the line relay of the automatic switch on the other end of the trunk line X is energized and the switch is prepared for operation in the usual manner. Current is now flowing through both the upper and lower windings of electropolarized relay 106 but the said relay is not energized at this time because the current flowing in either winding is opposite in direction to that flowing in the other.
- 10 The calling subscriber now manipulates his calling device in accordance with the next digit in the desired number, thereby producing a corresponding number of interruptions in the circuit of line relay 102.
- 20 Each time line relay 102 deenergizes in response to one of these interruptions it opens the circuit of the line relay of the automatic switch on the distant end of the trunk line at armature 114, thereby causing the said switch to operate in the usual manner. Slow acting relay 103 is maintained energized throughout the series of interruptions over a circuit which includes armature 113 and its resting contact and armature 118 and its working contact. Upon energizing, slow acting relay 103 completes the bridge across the conductors of the trunk line X by a more direct path, which excludes the right hand winding of impedance 107 and the upper winding of electropolarized relay 106 at armature 115 and its working contact. This is the usual expedient made use of in order to obtain first class switch control. At the end of the series of interruptions, line relay 102 comes to rest in an energized condition and slow acting relay 103, upon deenergizing, restores the bridge across the conductors of the trunk line X to its previously traced path.
- 30 The calling subscriber may now go ahead and dial the remaining digits of the desired number, the repeater F functioning for each digit in the manner described. When the connection is finally completed and the called subscriber has been signalled and has responded by removing his receiver, the current flow in the trunk line X and consequently in the bridge across the conductors of the said line in the repeater F is reversed by the final switch in the distant exchange. When this occurs, the two windings of electropolarized relay 106 which heretofore have opposed each other now assist each other in energizing the relay. Upon energizing, relay 106 places a shunt around armature 115 and its resting contact at armature 124; places a shunt around armature 114 and its working contact at armature 126; and at armature 125 closes the circuit of reversing relay 101. Upon energizing, reversing relay 101 shifts the bridge across the trunk line X so as to include both windings of impedance 107 at armature 112, and at armatures 110 and 111 reverses the incoming trunk conductors 76 and 78 as regards their connection with the upper and lower windings of line relay 102. This reversal of current flow is used in some cases to operate meters, coin boxes and the like but does not have anything in particular to do with the present invention, the circuits being shown in this manner because of the fact that it is more or less a standard arrangement. The calling and called subscribers may now converse with each other as desired, the talking circuits that are shown being outlined by heavy conductors.
- 40 When the conversation is completed the calling and called subscribers replace their receivers. When the receiver is replaced at the called substation the current flow in the conductors of the trunk line X is reversed back to normal whereupon electropolarized relay 106 retracts its armatures and upon so doing removes the shunt from around armature 115 and its resting contact at armature 124; removes the shunt from around armature 114 and its working contact at armature 126; and at armature 125 opens the circuit of reversing relay 101. Reversing relay 101, upon deenergizing, reverses the current flow in the calling subscriber's loop back to normal. This operation, however, does not perform any useful function in the present case.
- 50 When the receiver is replaced at the calling substation the circuit of line relay 102 of repeater F is opened and the said relay, upon deenergizing, opens the bridge across the conductors of the trunk line X at armature 114, whereupon, the automatic switches in the distant exchange restore themselves to normal position in the usual manner. As a further result of the deenergization of line relay 102, it opens the circuit of slow acting release relay 105 and closes the circuit of slow acting relay 103 at armature 115. Release relay 105, upon deenergizing, opens the circuit of relay 104 at armature 120. Relay 104, upon deenergizing, opens the circuit of slow acting relay 103 at armature 118 and at armature 117 removes ground from release trunk conductor 77. When ground is removed from release trunk conductor 77, relay 54 and switching relay 51 of the switch E³ and switching relay 14 of the selector D, together with the switching relays of the various other switches which were engaged in the connection before the selector D was reached, deenergize. The deenergization of the two relays mentioned in the switch E³ restores that switch to normal condition and connects up release trunk conductor 39 to common conductor 90 at armature 60.
- 60 In the selector D, switching relay 14, up-

on deenergizing, completes a circuit for release magnet 19 as follows: From ground by way of resting contact of armature 30 and said armature, armature 15 and its 5 resting contact, armature 17 and its resting contact, off-normal contacts 18, and release magnet 19 to battery. By the operation of the release magnet, the shaft and wipers of the selector D are restored to normal 10 position in the usual manner, the circuit of release magnet 19 being opened at off-normal contacts 18 by the switch shaft when it reaches normal position. The other switches engaged in the connection before 15 the selector D was reached are restored to normal position in the usual manner. The entire connection is now released and the apparatus is now ready for another call.

Referring now again to Figs. 3 and 4, the 20 function of the relay group RG, Figure 4, together with its associated equipment will now be explained in detail. We shall assume that the group of trunks, to which the switch E³ and others has access, is idle and 25 that a call comes in over one of the switches, the switch E³ for example. As soon as the trunk line comprising conductors 38, 39 and 40 leading to the switch E³ is seized by a selector such as the selector D, a ground 30 potential is thrown upon release trunk conductor 39 by the selector in order to make the seized trunk busy immediately. This ground potential, as hereinbefore pointed out, extends by way of the common conductor 90 to the release trunks of all the 35 switches, in that group. This ground potential extends also by way of conductor 90 to relay 130 of the relay group RG, Fig. 4. Relay 130, upon energizing, connects the 40 common conductor 90 with conductor 142 at armature 134. This operation, however, does not perform any particular function at this time. As soon as the various relays of the switch E³ have had time to function, 45 release trunk conductor 39 is disconnected from common conductor 90 at armature 60 of switching relay 51, whereupon relay 130 of relay group RG deenergizes and disconnects the common conductor 90 from conductor 142.

As a further result of the energization of 50 switching relay 51 of the switch E³, the trunk line extending to the repeater F is seized and the repeater is made ready for 55 operation in a manner hereinbefore explained. As soon as relay 105 of repeater F is energized, the first one of a chain of contacts in the circuit of relay 132 of relay group RG is closed at armature 121, and at 60 armature 122 the resistance 123 is disconnected from conductor 139 and ground is placed on the latter, thereby closing a circuit for relay 131 of relay group RG by way of armatures 138 and 137. A circuit is 65 closed at this time for relay 133 of relay

group RG as follows: From ground by way of conductor 139, armatures 122' and 122² in multiple and their resting contacts, resistances 123' and 123², conductor 141, and relay 133 to battery. Relays 131 and 133 70 energize simultaneously and the latter, upon energizing, opens the circuit of the former at armature 138, whereupon, the said relay 131 deenergizes. It is seen now that with one of the repeaters of the group comprising repeaters F, F' and F² busy, ground is placed on conductor 139 to close the circuit of relay 131 but relay 133 is energized and has the circuit of the former relay open. 75

We shall assume that another call comes 80 in and that one of the non-numerical switches in the group in which the switch E³ is located seizes one of the remaining repeaters, the repeater F² for example. As soon as the non-numerical switch is seized, 85 ground is placed on the common conductor 90 in a manner described before but does not produce any result in the relay group RG other than merely operating relay 130. As soon as the non-numerical switch has had 90 time to function and seize the repeater F² ground is removed from the common conductor 90 and relay 130 deenergizes. Relay 105² of the repeater F², upon energizing, 95 closes another point in the circuit of relay 132 at armature 121², removes the resistance 123² from the circuit of relay 133 and places a multiple ground on conductor 139 at armature 122². Relay 133, which is marginally 100 adjusted, deenergizes at this time since its circuit is closed through only the resistance 123' and completes the circuit of relay 131 at armature 138. Relay 131, upon energizing, 105 places ground on conductor 142 at armature 135. This is done in preparation so as to place ground on the common conductor 90 at relay 130 as soon as the sole 110 remaining outlet from this group is taken for use.

Assuming now that another non-numerical switch in this group is seized, ground is thrown upon common conductor 90 in the usual manner, whereupon relay 130 of the relay group RG energizes and connects the common conductor 90 with conductor 142 115 which is grounded at armature 135 of relay 131. As soon as the non-numerical switch has functioned, its release trunk is disconnected from the common conductor 90 and the repeater F' is seized in the usual manner. All the outlets from this group of 120 switches are in use and if another call were permitted to come into this group at this time it would be lost for the lack of an outlet. No call can come into this group at this time, however, for the reason that the common conductor 90 is maintained grounded by relay 130 of relay group RG and, consequently, the calls are shifted to such other 125 groups of non-numerical switches as have 130

idle trunks leading out from them. As soon as relay 105' of the repeater F' has energized in response to seizure of this repeater, it completely opens the circuit of relay 133 at armature 122'. This, however, does not produce any effect in the relay group RG as relay 133 is already deenergized. As a further result of the energization of relay 105' it completes the circuit of relay 132 at armature 121'. Relay 132, upon energizing, opens the circuit of relay 131 at armature 137 and at armature 136 places a multiple ground on conductor 142 and consequently on common conductor 90. Relay 131, upon deenergizing, disconnects conductor 142 from ground at armature 135 but the said conductor is still grounded at armature 136.

We shall assume for the sake of illustration that the subscriber who is using the switch E³ and the repeater F finishes his conversation and replaces his receiver. With the assumption as noted, the connection is released in a manner hereinbefore described and release trunk conductor 39 of the switch E³ is connected to the common conductor 90 again. As soon as relay 105 of repeater F deenergizes, a circuit is closed for relay 133 of the relay group RG in series with resistance 123 but owing to its marginal adjustment, relay 133 is not energized at this time. As a further result of the deenergization of relay 105, it opens the circuit of relay 132 at armature 121. Relay 132, upon deenergizing, removes ground from conductor 142 and consequently from the common conductor 90 at armature 136 and at armature 137 closes the circuit of relay 131. Relays 130 and 131 are so adjusted that the armature of relay 130 falls back slightly quicker than the armature of relay 131 is attracted and consequently relay 130 deenergizes at this time and disconnects the common conductor 90 from conductor 142 at armature 134 before relay 131 has had time to energize. The circuit conditions of the relay group RG are now the same as they were just before the repeater F' was seized, that is, conductor 142 is grounded and the circuits are in readiness for placing ground on the common conductor 90 as soon as the last outlet from this group is taken for use.

If we assume now that one of the repeaters F' or F², the repeater F² for example becomes idle, thus giving more than one available outlet from this group, before another call comes in to this group, the circuit of relay 131 is opened and ground is removed from conductor 142 as will now be pointed out. Relay 105², upon deenergizing, opens at armature 121² still another point in the circuit of relay 132 at armature 121², and at armature 122² places resistance 123² in multiple with resistance 123 whereupon the marginally adjusted relay 133 energizes

and opens the circuit of relay 131 at armature 138. Relay 131 now deenergizes and removes ground from conductor 142 at armature 135.

It will be seen now that each time a switch in this group is taken for use the common conductor 90, which has the release trunk conductors of all the idle inlets connected with it, is connected with the conductor 142 of the relay group RG, and if there is only one remaining outlet from the group there is a ground potential on conductor 142, and relay 130 will become locked. Consequently, when the switch cuts through and the last outlet is taken for use, conductor 90 is not cleared but remains connected with the grounded conductor 142, thereby busying all the inlets into this group. It is seen further that the seizure of the last outlet is accompanied by a transfer of the ground connection on conductor 142 so as to permit the unlocking of relay 130 as soon as an outlet again becomes available. The advantage of the arrangement described lies in the fact that when there is only one available outlet from a group, the busying of the inlets to such group will occur simultaneously with the seizure of the next switch, and all possibility of a call being extended to a secondary switch having no idle outlets is eliminated.

It is to be understood that this same arrangement of making incoming trunks busy may be used in a situation in which there are more outlets than are shown in the present drawings. When other outlets are added, the repeaters associated therewith, will have their "make busy" contacts connected in the same manner as those of the intermediate repeater F' and these other repeaters may be inserted between either the repeaters F and F' or the repeaters F' and F².

It will be convenient to explain at this time that the switch E³, Figure 3, may be given access to as many outgoing trunks as desired by adding more trunk selecting relays and that, without adding any relays or other equipment, an additional trunk can be connected to the resting contacts of armatures 71, 72, and 75 of relay 54. In that case, of course, the ground which is shown connected to the resting contacts of armature 72 is removed. With this extra trunk, if there is no ground on the resting contact of armature 72 of relay 54 when the switch E³ is seized, it being assumed of course that the trunk in question is idle, then the energization of line relay 50 is followed immediately by the energization of switching relay 51, which switches the connection through to the normally connected trunk line. In case still more trunks are desired they can be had, as before stated, by adding one relay

per trunk together with its associated armatures and contacts. Each of these added relays may have a spring assembly identical with that of relay 53 and may be inserted 5 either between relays 52 and 53 or between relays 53 and 54. This increase in trunk capacity may be carried out as far as is desired, or until the cost of the switch equals or surpasses the cost of a switch having a 10 mechanical step by step trunk selecting movement.

It will be stated at this point that switches similar to the switch E³, Fig. 3, are assumed to be used in the entire layout shown in 15 Figs. 1 and 2 with the exception of the group comprising switches H—H⁴, inclusive, which are of a different type. This assumption however is made solely for convenience and to avoid the necessity of duplicating the 20 layout, it being understood that in practice switches of one type or the other will ordinarily be used exclusively in any given situation.

Referring now particularly to Fig. 5, 25 which is a circuit drawing of the switches H, H', and H⁴, of the group comprising switches H—H⁴, inclusive, Fig. 2, the switches H² and H³ are omitted, their circuits being identical with the circuits of 30 switch H'. For the purpose of illustration it will be assumed that all the switches in the group comprising switches H—H⁴, inclusive, are idle at this time and that the switch H is seized from one of the selectors 35 which has access to the trunk line comprising conductors 201—203, inclusive. With the assumption as noted, a ground potential is placed upon the release trunk conductor 202 immediately by the selector so as to 40 make the seized trunk busy to the other switches having access to it. This ground potential extends by way of armature 216 and its resting contact, armature 233 and its resting contact, and armature 225 and its 45 resting contact, to common conductor 292 to which all the release trunk conductors of the incoming trunks are normally connected. This makes all the incoming trunks associated with this group temporarily busy and 50 prevents two calls from being received in this group simultaneously, the other calls being shifted to other groups. This ground potential extends also through armature 218 and its resting contact, armature 224 and 55 its resting contact, and armature 226 and its resting contact to conductor 294 to which the trunk selecting relays 210, 211, and 212 are normally connected. Similarly this ground potential extends by way of a similar series of armatures and contacts in the switch H' to conductor 295 to which all the relays of this switch are normally connected. The same thing is true for each of the other 60 switches in the group. The other terminal

of the relays 212, 246, and 249 are normally 65 connected to common conductor 289, and relay 211 together with the similarly located relays in the other switches is connected to the common conductor 287. Neither common conductor 287 nor common conductor 70 289 has a battery potential on it at this time and consequently none of the relays mentioned energize. Common conductor 285, to which relay 210 and the similarly located relays in the other switches are normally 75 connected, is connected to battery at this time through the resting contact of armature 221 and said armature, resting contact of armature 232 and said armature, similar contacts and armatures on the switches H² 80 and H³, and the resting contact of armature 252 and said armature. That being the case, the first relay in each switch in this group starts to energize as soon as ground is placed upon release trunk conductor 202 as previously described. Relay 210, upon energizing, disconnects release trunk conductor 202 from common conductor 292 at armature 216, thereby making the remaining switches in this group accessible and allowing all the 90 other relays that started to pull up, responsive to the placing of a ground potential on conductor 292, to fall back. As a further result of the energization of relay 210 it locks itself to release trunk conductor 202 95 and disconnects itself from conductor 294 at armature 219; locks itself to battery and disconnects itself from common conductor 285 at armature 220; places ground on conductor 290 at armature 217; disconnects release trunk conductor 202 from conductor 294 at armature 218; removes battery from conductor 285 and places it upon conductor 286 at armature 221; connects release trunk conductor 202 with release trunk conductor 100 276 of the seized trunk at armature 216; and at armatures 215 and 222 connects conductors 201 and 203 with conductors 275 and 277 of the seized trunk. The line and release relays of the automatic repeater to 105 which the trunk line comprising conductors 275—277, inclusive, extends, immediately energize and prepare the switch for operation in the usual manner, and the latter, upon energizing, places ground upon release trunk conductor 276 thereby establishing the usual holding circuit.

The calling subscriber may now go ahead 110 and dial the remaining digit of the desired number in the usual manner.

If we assume that another call comes in at this time and that the switch H' is the one seized, a ground potential is sent forward over the release trunk conductor 205, through the series of contacts shown, to common conductor 292 and thence to the release conductors of all the idle switches in this group. The battery potential which was 125

placed on conductor 286 by the energization of relay 210 as explained now extends by way of armature 255 and its resting contact, similar armatures and contacts in switches 5 H^3 and H^2 , armature 239 and its resting contact, and armature 264 and its resting contact to conductor 287. Accordingly relay 245 and the corresponding relays in the switches H^2 — H^4 , inclusive start to energize 10 as soon as the ground potential is thrown upon release trunk conductor 205. There is no battery potential on common conductors 285 and 289, however, and consequently the associated relays do not energize. Relay 15 245, upon energizing, disconnects release trunk conductor 205 from common conductor 292 at armature 234, whereupon, all the other relays which started to energize at this time deenergize and the remaining idle 20 switches are made accessible again. As a further result of the energization of relay 245 it locks itself to release trunk conductor 205 and disconnects itself from conductor 295 at armature 237; locks itself to battery 25 and disconnects itself from conductor 287 at armature 238; extends the ground potential which is on conductor 290 to conductor 291 at armature 235; disconnects release trunk conductor 205 from conductor 295 at 30 armature 236; disconnects battery from conductor 287 and extends it to conductor 288 at armature 239; connects release trunk conductor 205 with release trunk conductor 279 of the seized trunk at armature 234; and at 35 armatures 233 and 240 connects conductors 204 and 206 with trunk conductors 278 and 280 of the seized trunk. The line and release relays of the switch to which the trunk line comprising conductors 278—280, inclusive, extends now energize in the usual manner and the latter places ground on release trunk conductor 279, thereby establishing the usual holding circuit. 40 Assuming now that another call comes in to this group and that it takes the switch H^4 , the ground potential which is placed upon release trunk conductor 208 is extended forward to common conductor 292 and thence to the release trunk conductors of the switches in this group which are idle 45 at this time. The battery potential which was placed upon conductor 288 by the energization of relay 245 of the switch H^4 extends by way of armature 262 and its resting contact, corresponding armatures and contacts in the switches H^3 and H^2 , armature 243 and its resting contact, and armature 227 and its resting contact to conductor 289. As a result relay 249 and the corresponding relays in switches H^3 and H^2 commence to energize as soon as the ground potential is placed upon release trunk conductor 208. In this case there is no battery potential upon conductors 285 and 287 and consequently neither relay 247 nor 248 of 50 55 60 65 70 75 80 85 90 95 100 105 110 115 120 125 130 the switch H^4 nor the corresponding relays in the other switches in this group which are idle at this time can energize. Relay 249, upon energizing, removes the ground potential from common conductor 292 at armature 237, whereupon the corresponding relays in the switches H^2 and H^3 , Fig. 2, fall back. As a further result of the energization of relay 249 it locks itself to release trunk conductor 208 and disconnects itself from conductor 295 at armature 260; locks itself to battery and disconnects itself from conductor 289 at armature 261; extends the ground potential which is on conductor 291 to common conductor 292 at armature 258; disconnects release trunk conductor 208 from conductor 295 at armature 259; disconnects battery from conductor 289 at armature 262; connects release trunk conductor 208 with release trunk conductor 282 of the seized trunk at armature 257; and at armatures 256 and 263 connects up conductors 207 and 209 with conductors 281 and 283, respectively, of the trunk line comprising conductors 281—283, inclusive. The line and release relays of the switch to which the seized trunk extends now energize in the usual manner and the latter places ground on release trunk conductor 282 thereby establishing the usual holding circuit. All the outlets from this subgroup of switches are now in use and if a call were permitted to come into this group at this time it would be lost for the lack of an outlet. Calls are prevented from coming into this group at this time by the ground potential which is extended forward by way of conductors 290 and 291 to common conductor 292 to which the release trunk conductors of the idle switches H^2 and H^3 are connected. In case the switch H becomes idle the battery potential will be replaced upon common conductor 285 thus making the first outgoing trunk available, and at the same time ground is removed from conductor 290 and consequently from common conductor 292 thus making the idle switches in this group available again. On the other hand if we consider that the switch H' becomes idle while the switch H is yet busy the battery potential will be replaced on common conductor 287 instead of on common conductor 285 thus making the second trunk line in the group available. It will be noted that these switches H — H^4 , inclusive, always take the first trunk when it is idle, taking the second trunk only when the first trunk is busy and the third only when the second trunk is busy. This, while not objectionable perhaps from a theoretic standpoint, is sometimes undesirable from a practical standpoint owing to the fact that all the trunk lines are not used alike and the switches associated with the

trunks which are used the most are subjected to the most wear and may have to be replaced often while the others are practically unused except during the peak of the 5 load which occurs periodically. This seeming difficulty can be obviated, if desired, in a manner which will now be pointed out. Working contacts may be placed on armatures 227, 243, corresponding armatures on 10 switches H² and H³, and armature 262 to which a common conductor may be wired. This common conductor may be extended to armature 252 of relay 247. This makes the battery transfer circuit a complete loop. 15 With this loop wired as described the battery connection may be removed from armature 252 and placed on either armature 255 or armature 262, thus making the associated trunk line first choice. Any suitable 20 method or means for shifting the battery potential from one armature to the other may be employed, for example, it may be shifted periodically by an attendant by means of the switch S, or it may be shifted 25 upon the extension of each call by a master switch arrangement.

It is to be understood that in case more outgoing trunks are desired they may be had by adding one relay to each switch together with the proper contacts and associated conductors. These relays may be inserted between the row comprising relays 211, 245, etc. and the row comprising relays 212, 246, etc., or between the first named 30 row and the row comprising relays 210, 244, etc. It is to be understood also that more switches may be added in a group and that each added switch will be similar to the switch H' and may be inserted anywhere along the line between the switches H and H⁴.

While the explanation might be still further amplified it is thought that the foregoing is sufficient to enable the invention 45 to be thoroughly understood by those who are skilled in the art and to whom this specification is directed.

The various features of the invention having been thus described and ascertained will 50 now be pointed out in the appended claims.

What is claimed is:

1. In a telephone trunking system, a trunking section comprising a plurality of similar groups of inlets and a group of outlets divided into a plurality of subgroups, the number of outlets in each subgroup being always equal to the total number of outlets divided by the number of inlets in a group, irrespective of the total number of 55 such outlets, and switching means for connecting inlets which are taken for use with idle outlets.

2. In a telephone trunking system, a trunking section comprising a plurality of 60 similar groups of inlets and a group of outlets divided into a plurality of subgroups, the number of outlets in each subgroup being always equal to the total number of outlets divided by the number of inlets in a group, irrespective of the total number of such outlets, and switching means for connecting inlets which are taken for use with idle outlets.

lets divided into a plurality of subgroups, the number of such subgroups being always equal to the number of inlets in a group, irrespective of the total number of outlets, and switching means for connecting inlets 70 which are taken for use with idle outlets.

3. In a telephone system, a secondary trunking section, step by step selector switches, trunks incoming to said section from said selector switches, trunks outgoing from said section, each of said trunks comprising two talking conductors, and switching means in said section consisting solely of relays for connecting incoming trunks which are taken for use with idle 75 outlets.

4. In a telephone system, a secondary trunking section, step by step selector switches, trunks incoming to said section from said selector switches, trunks outgoing from said section, each of said trunks comprising two talking conductors, a plurality of switching devices consisting solely of relays, each incoming trunk being terminated in one of said devices, and means for energizing a relay in the associated switching device when an incoming trunk is taken for use to connect such trunk with an idle outgoing trunk.

5. In a telephone system, a line terminating in an automatic switch, said switch comprising a series of connecting relays, a group of trunk lines accessible to said switch, there being one trunk line for each connecting relay, means responsive to a call on said first line for energizing and deenergizing a plurality of said relays in a definite order to connect said first line with successive trunk lines, and means for preventing the energization of any more of said relays as 100 soon as a relay is energized which is associated with an idle trunk line.

6. In a telephone system, means for establishing a talking connection including an automatic trunk selecting switch, a line relay and a plurality of trunk connecting relays included in said switch, and circuits controlled by said line relay upon a single energization thereof for energizing a plurality of said connecting relays successively 105 to test for and select an idle trunk.

7. In a telephone system, means including an automatic trunk selecting switch for connecting calling and called lines, said switch having access to a plurality of trunks and being provided with as many trunk connecting relays as there are trunks, a line relay in said switch, and circuits controlled by said line relay responsive to a call for energizing said connecting relays in a definite 120 order until an idle trunk line is selected.

8. In a telephone system, means including an automatic trunk selecting switch for connecting calling and called lines, said switch having access to a plurality of trunks and 130

- being provided with as many trunk connecting relays as there are trunks, a line relay in said switch, circuits controlled by said line relay responsive to a call for energizing 5 said connecting relays in a definite order until an idle trunk line is selected, and a circuit independent of said line relay for maintaining the last energized connecting relay in operated position.
9. In a telephone system, means including an automatic trunk selecting switch for connecting calling and called lines, said switch having access to a plurality of trunks and being provided with as many trunk connecting relays as there are trunks, a line relay in said switch, a circuit completed by the line relay for energizing the first connecting relay, a circuit completed by each connecting relay for energizing the next connecting relay, and testing means for preventing the energization of any more connecting relays as soon as a connecting relay corresponding to an idle trunk line is energized.
10. In a telephone system, means including an automatic trunk selecting switch for connecting calling and called lines, said switch comprising a series of trunk connecting relays and a cooperating switching relay, a circuit for energizing a connecting relay, and a circuit for energizing the switching relay in series with the next connecting relay.
11. In a telephone system, an automatic trunk selecting switch for use in connecting calling and called lines, said switch comprising a switching relay and a series of trunk connecting relays, means for closing a circuit including the switching relay and the first connecting relay, trunk testing means adapted to short circuit the switching relay and cause the energization of the said first connecting relay, and switching means for substituting the second connecting relay in said circuit in place of the first connecting relay.
12. In a telephone system, an automatic trunk selecting switch for use in connecting calling and called lines, said switch comprising a switching relay and a series of trunk connecting relays, a trunk testing circuit and cooperating circuit transferring means for energizing a plurality of said connecting relays in order until a relay is energized which is associated with an idle trunk line, and a circuit for said switching relay constituting a branch of said testing circuit.
13. In a telephone system, an automatic trunk selecting switch for use in connecting calling and called lines, said switch comprising a switching relay and a series of trunk connecting relays, a circuit for said switching relay, circuit transferring means for altering said circuit to include successive connecting relays, and a testing conductor connected to said circuit for short circuiting said switching relay and for energizing the connecting relays.
14. In a telephone trunking system, a plurality of incoming trunks each terminating in a switching mechanism, a lesser plurality of outgoing trunks accessible in common to all said mechanisms, and means effective whenever there is only one idle outgoing trunk for making all remaining incoming trunks busy when the next incoming trunk is taken for use.
15. In a telephone trunking system, a plurality of incoming trunks each terminating in a switching mechanism, a lesser plurality of outgoing trunks accessible in common to all said mechanisms, and means effective in case there is only one outgoing trunk available when an incoming trunk is taken for use for simultaneously making such incoming trunk and the remaining idle incoming trunks busy.
16. In a telephone trunking system, a plurality of incoming trunks each terminating in a switching mechanism, a lesser plurality of outgoing trunks accessible in common to all said mechanisms, means effective in case there is only one outgoing trunk available when an incoming trunk is taken for use for simultaneously making such incoming trunk and the remaining idle incoming trunks busy, and means for maintaining such other incoming trunks busy until an outgoing trunk becomes idle.
17. In a telephone trunking system, a plurality of incoming trunks each terminating in a switching mechanism, a lesser plurality of outgoing trunks accessible in common to all said mechanisms, means effective in case there is only one outgoing trunk available when an incoming trunk is taken for use for simultaneously making such incoming trunk and the remaining idle incoming trunks busy, and means for removing the busy condition on such remaining incoming trunks when any outgoing trunk becomes idle.
18. In a telephone trunking system, a plurality of incoming trunks each terminating in a switching mechanism, a lesser plurality of outgoing trunks accessible in common to all said mechanisms, and means for making all idle incoming trunks busy whenever any incoming trunk is taken for use.
19. In a telephone trunking system, a plurality of incoming trunks each terminating in a switching mechanism, a lesser plurality of outgoing trunks accessible in common to all said mechanisms, means for making all idle incoming trunks busy when an incoming trunk is taken for use, and means for removing the busy condition on the idle incoming trunks as soon as the switching

- mechanism associated with the incoming trunk in use is operated to select an idle outgoing trunk.
20. In a telephone trunking system, a plurality of incoming trunks each terminating in a switching mechanism, a lesser plurality of outgoing trunks accessible in common to all said mechanisms, means for making all idle incoming trunks busy when an incoming trunk is taken for use, means for removing the busy condition on the idle incoming trunks as soon as the switching mechanism associated with the incoming trunk in use is operated to select an idle outgoing trunk, and means for preventing such removal of the busy condition in case no more outgoing trunks are idle.
21. In a telephone trunking system, a plurality of incoming trunks each terminating in a switching mechanism, a lesser plurality of outgoing trunks accessible in common to all said mechanisms, and release trunk conductors for said incoming trunks all normally connected together over paths excluding any magnet windings of said switching mechanisms.
22. In a telephone trunking system, a plurality of incoming trunks each terminating in a switching mechanism, a lesser plurality of outgoing trunks accessible in common to all said mechanisms, a release trunk conductor included in each incoming trunk, and means effective when an incoming trunk is taken for use for simultaneously grounding the release trunk conductor associated with such incoming trunk and the release trunk conductors which are associated with all the other idle incoming trunks.
23. In a telephone trunking system, a plurality of incoming trunks each terminating in a switching mechanism, a lesser plurality of outgoing trunks accessible in common to all said mechanisms, and means for busying the excess incoming trunks when the outgoing trunks are all in use, said means including two relays, with means for energizing one relay when all but one of said outgoing trunks are busy and means for energizing the other relay when all of said outgoing trunks are busy.
24. In a telephone trunking system, a plurality of incoming trunks each terminating in a switching mechanism, a lesser plurality of outgoing trunks accessible in common to all said mechanisms, a release trunk conductor associated with each incoming trunk, means for grounding all the release trunk conductors associated with idle incoming trunks at one point when an incoming trunk is taken for use, means for grounding said release trunk conductors at another point while the switching mechanism associated with the incoming trunk in use is being operated, and means for grounding said release trunk conductors at still another point in case there is only one idle outgoing trunk available for selection by said switching mechanism.
25. In a telephone trunking system, a plurality of incoming trunks, a lesser plurality of outgoing trunks, switching mechanisms whereby any incoming trunk may be connected with any outgoing trunk, a release trunk conductor included in each incoming trunk, and means effective when an incoming trunk is taken for use for simultaneously grounding the release trunk conductor associated with such incoming trunk and the release trunk conductors which are associated with all the other idle incoming trunks.
26. In a telephone trunking system, a plurality of incoming trunks, a lesser plurality of outgoing trunks, switching mechanisms whereby a connection may be effected between any incoming trunk and any outgoing trunk, and means for busying the excess incoming trunks when the outgoing trunks are all in use, said means including two relays, with means for energizing one relay when all but one of said outgoing trunks are busy, and means for energizing the other relay when all of said outgoing trunks are busy.
27. In a telephone trunking system, a trunking unit comprising a plurality of incoming trunks, a lesser plurality of outgoing trunks, and switching mechanisms whereby a connection may be effected between any incoming trunk and any outgoing trunk, means for making all idle incoming trunks busy responsive to the taking for use of a single incoming trunk, means responsive to the completion of a connection between said single incoming trunk and an outgoing trunk for removing the said busy condition from the remaining idle incoming trunks, and means common to the trunking unit for placing a further busy condition on the remaining idle incoming trunks prior to the said removal of the first busy condition in case only one outgoing trunk is idle when the said single incoming trunk is taken for use.
28. In a telephone trunking system, a plurality of incoming trunks, a lesser plurality of outgoing trunks, switching mechanisms whereby a connection may be effected between any incoming trunk and any outgoing trunk, means for operating one of said switching mechanisms when an incoming trunk is taken for use to effect a connection between such incoming trunk and an idle outgoing trunk, and means responsive to the taking of such incoming trunk for use for making other incoming trunks busy before the last named mechanism is operated.
29. In a telephone trunking system, a plurality of incoming trunks, a lesser plurality

of outgoing trunks, switching mechanisms whereby a connection may be effected between any incoming trunk and any outgoing trunk, means for operating one of said switching mechanisms when an incoming trunk is taken for use to effect a connection between such incoming trunk and an idle outgoing trunk, and means responsive to the taking of such incoming trunk for use and independent of the said operation of the last named switching mechanism for making other incoming trunks busy.

In witness whereof, I hereunto subscribe my name this 28th day of September, A. D., 1921.

RODNEY G. RICHARDSON.
